COMBINED TABLE AND MULTIPLE SEAT UNIT

Charles H. Gerber, P.O. Box 181,
Middleton, Wis. 53562

Filed Aug. 14, 1975, Ser. No. 604,559

Term of patent 14 years

Int. Cl. D6—05

U.S. Cl. D6—45

FIG. 1

FIG. 2

FIG. 3

FIG. 1 is an isometric view of my combined table and multiple seat unit.

FIG. 2 is an end view of my combined table and multiple seat unit, the opposite end being identical.

FIG. 3 is a side view of my combined table and multiple seat unit, the opposite side being identical.

I claim:

The ornamental design for a combined table and multiple seat unit, as shown and described.
